Primary Examiner — Susan E Krakower*Assistant Examiner* — Jerry Shuan-Hua Hsu(74) *Attorney, Agent, or Firm* — Jason P. Webb; Pearson Butler(57) **CLAIM**

The ornamental design for a fold-down deck as shown and described.

DESCRIPTION

FIG. 1 is a front-top perspective view of a fold-down deck, in retracted mode, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

Fig. 7 is a left side elevational view thereof;

FIG. 8 is a front-top perspective view of a fold-down deck, in an extended mode;

FIG. 9 is a left side elevational view thereof;

FIG. 10 is a front-top perspective view of a fold-down deck, in a folded retracted mode; and,

FIG. 11 is top plan view thereof.

The broken lines illustrate portions of the fold-down deck which form no part of the claimed design.
